UNITED STATES PATENT OFFICE.

AGATHOPOULOS PALIS, OF NEW YORK, N. Y.

COLLAR.

1,181,342.

Specification of Letters Patent.

Patented May 2, 1916.

Application filed May 18, 1915. Serial No. 28,830.

To all whom it may concern:

Be it known that I, AGATHOPOULOS PALIS, a subject of the King of Greece, residing at 45 West Twenty-ninth street, in the city, county, and State of New York, have invented new and useful Improvements in Collars, of which the following is a specification.

My invention relates to shirt collars and particularly to those of the turn-down type.

With an ordinary turn-down collar, wherein the neck-tie used is passed completely around the same through the space between folds, great difficulty is experienced in adjusting the tie while the knot is being tied, owing to the fact that the tie binds between the folds. Numerous ways have been devised for overcoming this difficulty, but in so far as I am aware no truly practical and efficient construction has been produced.

It is therefore my purpose to provide a collar which is not open to the disadvantage mentioned, and which is capable of retaining extremely short neck-ties, whereby the latter may be manufactured at a reduction in labor and cost of material.

To these ends the invention consists in the combination and construction of parts hereinafter more particularly set forth and claimed, and illustrated in the accompanying drawing, in which:

Figure 1 is a perspective view of a collar constructed in accordance with the preferred embodiment of the invention, one corner of the outer fold being upturned to reveal the flap construction; Fig. 2 is a bottom plan view partly broken away, the outer fold having its normal form; Fig. 3 is a perspective view of a modified form of the device, partly broken away; and Fig. 4 is a front elevation of a portion of the preferred form collar, partly in section, showing the manner in which a necktie is applied to the slotted flaps.

Referring to the drawing, in Figs. 1 and 2, the preferred embodiment of the invention is illustrated, wherein a turndown collar is provided between its inner and outer folds 1 and 2 respectively, with vertically extending flaps 3 which project outward from the inner fold adjacent to the respective attaching tabs 4 of the collar. These flaps are formed by doubling the inner fold 1 at these points and then stitching the doubled portions together to form the desired

flaps. The flaps 3 are provided with vertically extending slots 5 which are substantially co-extensive and are adapted to have a neck-tie threaded therethrough in the manner indicated, when the collar is properly applied to the neck-band of a shirt. When the collar is thus applied, the outermost attaching tab 4 will have its end engaged between the inner tab and the corresponding slotted flap, it being understood that both collar tabs are equal in length. The outer tab will thus be secured against displacement in an effective manner and will not interfere with the attachment of the tie to the flaps in the manner shown in Fig. 5 of the drawing.

In Fig. 3 a modification is illustrated. In this instance, a detachable member 6 in the form of an elongated strip is provided for interchangeable use in connection with various forms of turn-down collars. This strip is intended to be constructed substantially equal in length to a collar of a given size and is adapted to be inserted between the folds of the same. This strip is provided medially and in its end tabs with button-holes 7 and 8 respectively, which are adapted to register with the corresponding button-holes of the collar proper. Slotted flaps 9 are provided upon this strip and are relatively situated the same as the integrally formed flaps shown in Figs. 1 and 2 of the drawing.

It is obvious that the detachable member just described may be used in connection with a great number of collars of the proper size, and its use will not involve the remodeling of those collars which are in use at the present time.

In a collar constructed in accordance with either form of the invention it is desirable that the slotted flaps shall be spaced a considerable distance apart, but free access thereto must be possible. In order to permit this spacing of the flaps and at the same time facilitate the application of neck-ties thereto, the meeting edges of the outer fold of the collar are provided with registering recesses 10 which are substantially co-extensive with the slots in the flaps. These recesses open through the lower edge of the said collar fold but are spaced from the creased upper edge of the collar in order that the upper edges of the attaching tabs will not be exposed for irritating contact with the neck of the wearer. The space

provided by these co-acting recesses will also accommodate the knot of the tie both during and after adjustment of the same.

Having thus described my invention, 5 what I desire to claim and secure by Letters Patent is:

A turn-down collar having tie-attaching flaps projecting outwardly with respect to its inner fold into the tie space and located 10 adjacent to the meeting ends of the collar, the said flaps being provided with vertically

extending tie slots, the ends of the outer fold being recessed substantially co-extensive with the slots of said flaps and in spaced relation to the crease of the collar, 15 the vertical edge of each recess being contiguous to the vertical edge of the corresponding flap.

In testimony whereof I have signed my name to this specification.

AGATHOPOULOS PALIS.
